UNITED STATES PATENT OFFICE.

ELMER SEVERSON, OF DEERFIELD, WISCONSIN.

CHAIN SNAP LOCK.

Application filed January 2, 1925. Serial No. 292.

To all whom it may concern:

Be it known that I, ELMER SEVERSON, a citizen of the United States, residing at Deerfield, in the county of Dane and State of Wisconsin, have invented certain new and useful Improvements in Chain Snap Locks, of which the following is a specification.

My invention relates to chain snap locks for tie chains for horses and cattle; and the object of my invention is to provide a locking member which will prevent the shackle being forced backward against the spring actuated sliding bolt, and the shackle allowed to drop down.

I attain this object by the mechanism shown in the accompanying drawing in which—

Fig. 1 is a plan;

Fig. 2, is a side elevation, with the shackle closed;

Fig. 3, is a vertical longitudinal section, on line 3—3 Fig. 1;

Fig. 4, is a side elevation, with shackle open;

Fig. 5, is a plan of the sliding bolt;

Fig. 6, is a transverse vertical section on line 6—6 Fig. 2.

Similar numerals refer to similar parts throughout the several views.

The body 1 is of sheet metal in the form of a square tube for the distance of approximately two thirds its length, then the bottom plate 2 is removed, and the side walls 3 are slightly tapered to the front end. A mortise 3^a is pierced through the top plate 4 adjacent the front end and extends backward a distance sufficient for the U shaped portion of a shackle 17 to pass downward through the same, and of a width equal to the inside diameter of the body. A second mortise 3^b is pierced through the top plate 4 adjacent the rear end of mortise 3^a and extends backward a distance slightly more than the width of the depending lock-hook 5 on the locking member 5^a. A third mortise 3^c is pierced through the top plate 4 and the bottom plate 2 adjacent the rear end of the body and on the left side thereof, said mortise being in vertical alignment with a groove 4^a in the left side of the plug 6^a is adapted for inserting a pin 6^b and thereby securing the swivel 7 to the body. A spring 8 is disposed in the body contig-

uous the front end of the plug 6^a and extends forward to contact a sliding lock-bolt 9, said lock-bolt as seen in Fig. 5 is square on the front end with a central groove 10 vertically for admitting a key 11 and a portion 12 is removed from the right side to allow the lock-hook 5 to pass below the arm 13 on the rear end of the slide, a portion 14 is also removed from the top of the slide through which a pin 15 passes to restrict the movement of the same longitudinally of the body. Two slotted straps 16 are pivotally connected to the rear end of the shackle 17 by a pin 18, and the locking member 5^a is slidably secured between the straps by a pin 19 loosely disposed in the slots 20. A chain 21 may be secured to the swivel 7 by the pin 22.

To secure the snap to any link in a chain, hook the shackle 17 through the link and force backward the sliding lock-bolt 9 until the front end of the shackle will pass upward through the mortise 3^a, then force downward the lock-hook 5 through the mortise 3^b until the hook engages and forces backward the arm 13 and passes below it, thereby closing the mortise 3^b and preventing the shackle being moved backward, until the key 11 is inserted in the slot 10 and the sliding lock-bolt 9 is forced backward sufficient to remove the arm 13 from contact with the hook 5.

Having thus described my invention, I claim:

In a lock for tie chain snaps comprising a hollow body with a spring actuated slideable bolt within the body, a shackle adapted to pass transversely through the body with a member loosely connected to the rear end of the shackle by slotted straps, a portion of said member extending downward in the form of a hook, and adapted to be inserted through a mortise in the top of the body and engage the slideable bolt, in combination with a key for disengaging the bolt from the hook.

In testimony whereof I affix my signature in the presence of two subscribing witnesses.

ELMER SEVERSON.
